UNITED STATES PATENT OFFICE.

AMOS MADSON, OF PONTIAC, ILLINOIS.

SHOE.

1,265,100.

Specification of Letters Patent.

Patented May 7, 1918.

Application filed November 26, 1917. Serial No. 204,079.

To all whom it may concern:

Be it known that I, AMOS MADSON, a subject of the King of Norway, residing at Pontiac, in the county of Livingston and State of Illinois, have invented a new and useful Shoe, of which the following is a specification.

The present invention appertains to footwear, and aims to provide a novel and improved construction and assemblage of the component parts of a shoe, boot, sandal or other article of footwear, the term "shoe" being employed herein for convenience, to designate broadly any article of footwear. 10 One of the objects of the invention is the provision of a "welt" shoe eliminating the use of a separate insole as customarily employed, and otherwise improving and facilitating the construction and assemblage of 15 parts of the shoe to lessen the cost of production, and at the same time to render the shoe more flexible and efficient.

A further object of the invention is the provision of novel means for joining the upper and its lining with the sole in such a manner as to make a substantial and secure construction.

Another object of the invention is the provision of novel means for uniting the heel, upper and sole to provide an effective and practical construction.

The invention also aims to provide a shoe of the nature indicated, which will permit of repairs being readily made, to resole or apply a new sole to the shoe readily and perfectly, either by stitching, pegging or nailing operations.

With the foregoing and other objects in view, which will appear as the description 40 proceeds, the invention resides in the combination and arrangement of parts and in the details of construction hereinafter described and claimed, it being understood that changes can be made in the precise embodiment of the invention herein disclosed, within the scope of what is claimed, without departing from the spirit of the invention.

The invention is illustrated in the accompanying drawings, wherein:

50 Figure 1 is a plan view of the sole cut ready for the attachment of the upper and showing the shank thereon.

Fig. 2 is a cross section on the line 2—2 of Fig. 1.

55 Fig. 3 is a cross section on the same line

showing the first steps in attaching the upper and sole together.

Fig. 4 is a fragmental bottom plan view illustrating the attachment of the upper to the heel seat of the sole.

Fig. 5 is a cross section on the same lines as in Figs. 2 and 3, showing the completed construction.

Fig. 6 is a cross section on the line 6—6 of Fig. 4 showing the completed heel construction.

Fig. 7 is a side elevation of the finished product or shoe.

Fig. 8 is a sectional detail of a modification.

Fig. 9 is a similar view showing a further stage of completion of the modification.

Fig. 10 is a fragmental cross section showing a slight modification in the invention.

In carrying out the invention, the sole 1 is cut to suitable shape, being provided at its rear or heel end with a heel seat 2 of reduced width, forming the shoulders 3 between the shank portion and heel seat. The sole is channeled around its margin from one shoulder 3 to the other, to provide a feather which is turned up to provide a flexible lip 4 along the inner edge of the sole. The lip 4 extends between the shoulders 3. The lip 4 is in the form of a flexible flap which is turned upwardly from the margin of the sole, and provides a wing 7 of reduced thickness. The sole is provided with a groove 8 between the marginal portion or wing 7 of the sole and the lip 4, said groove being extensive in length with the wing 7 which extends from one shoulder 3 to the other around the forward or toe end of the sole.

The sole is further prepared by cutting a channel 9 upwardly and outwardly therein in its lower surface, said channel being located inwardly of the wing 7, and being extensive in length therewith. The channel 9 extends upwardly and outwardly toward the groove 8 and is provided with a groove 10 spaced inwardly of and in substantially the same horizontal plane as the groove 8 to receive the stitching forming the inseam. The channel 9 forms a flexible lip 11 underneath the same projecting inwardly.

The upper 12 is provided with a lining 13 therein, and in assembling the upper and its lining with the sole, they are placed over a suitable last, shaped or grooved to receive

the lip 4. The wing 7 is then bent or folded back against the bottom surface of the sole, as seen in Fig. 3, and the marginal portion of the upper and its lining is then placed against the lip 4, and said marginal portion of the upper, with the lining, is placed snugly around the bend of the wing 7, to overlap said wing, as seen in Fig. 3. The marginal portions of the upper and lining 10 are held in place, together with the wing 7, by tacking them to the sole, the tacks 14 extending through the upper, lining and wing 7 and extending into the sole, as seen in Fig. 3. While the parts are thus held 15 in place, the welt 15 is passed around the upper, lying snugly thereagainst with its lower edge portion at that side of the upper opposite to the groove 8, and the upper or outer edge portion of the welt extending 20 upwardly. The welt, upper, lining and sole are then fastened together by means of stitching 16 or other securing means extending through the welt, upper and lining within the groove 8 and horizontally 25 through the sole between the grooves 8 and 10, the channel 9 permitting of such sewing through the parts as described. The upper and lining are then cut off immediately below the welt 15, at the point X, to remove 30 the surplus material, and the wing 7 is released by withdrawing the tacks 14, thus permitting the wing to spring back into former shape. The stitching or securing means 16 provides an inseam which is covered by the welt 15, and the lower edges of the upper 12 and lining 13 and inner edge of the welt 15, forming a bead which is seated snugly in the groove 8. The inner edge of the welt is thus secured to the sole 40 through the upper and lining from below, and the welt extends upwardly and outwardly over the inseam or securing means to cover the same and provide a neat finish.

The upper 12 and lining 13 are then cut 45 or slit at Y, adjacent to the shoulders 3, whereby the lower marginal portions thereof can be turned to overlap the bottom surface of the heel seat 2, as at 17, and said marginal portion of the heel or counter portion 50 of the upper is then secured to the heel seat 2 by means of tacks 18 or the like driven through the portion 17 and into the heel seat. The counter 19, which is disposed between the upper 12 and lining 13, is also 55 fastened to the lower surface of the heel seat by the tacks 18.

A lift 20 is then placed against the portion 17 and heel seat 2 and secured thereto by means of tacks 21 or other securing 60 means driven through the lift and into the heel seat, thus covering the portion 17. The forward or shank edge of the lift 20 is beveled or chamfered at its upper surface, as at 22, to form a better and stronger connection with the sole, and the beveled surface 65 22 fits snugly against the sole, the shoulders 3 and heel ends of the welt 15 being beveled, as at 23, to fit the beveled surface 22, thus providing a neat joint at the side edges, where the parts are exposed. The welt 15 is 70 then sewed down on the wing 7 by means of stitching 24 or other securing means extending through the welt and wing, and said securing means 24 also extending through the heel or rear ends of the wing 7, welt 15 and 75 lift 20 where they have the lap or scarf joint, thus uniting said parts together firmly above the breast of the heel. In thus extending the stitching or securing means 24 back far enough, it not only unites the 80 welt and wing 7, but also unites the shank edge of the lift 20 with said wing and welt.

The shank 25 which is placed on the sole 1 is then stitched on the sole by means of stitching 26 or other securing means passing 85 through the shank and sole, said stitching or securing means 26 being within the channel 9 or its groove 10 through which the stitching 16 also extends. The lip 11 is then brought flush with the lower surface of 90 the sole by cementing or other fastening means, and it is preferable to run stitching 27 or other securing means through the upper, lining and lip 4. This makes a secure 95 connection between the lip and vertical portion of the upper above the wing 7, and said lip provides a shoulder or abutment against which the upper is secured. The lip 4 can be made relatively narrow, and pressed down flat as shown in Fig. 5, but it can have 100 a feather edge to overlap the lining and receive the pressure of the foot.

Finally, the heel 28, composed of lifts, is fastened by nails, pegs or other securing means to the lift 20 and adjacent parts. 105 This completes the shoe.

It will be seen, from the foregoing, that the present construction produces a lined "welt" shoe requiring no occasion for the use of an insole, the lip 4 meeting all the demands as an equivalent for an insole. The welt or stitched down process can be used with lips of various forms, or the lips can be cut off when not wanted.

In the modification shown in Figs. 8 and 115 9, the welt 15 is omitted, and the wing 7 is made thicker and the groove 8 therefore deeper. In this modification the wing 7 has a flexible lip 30 projecting inwardly and overhanging the groove 8', which can be 120 bent back upwardly and outwardly, as seen in Fig. 8, when the upper 12 and lining 13 are stitched within the groove 8', by the stitching 16, as above described. Then, when the upper and lining are cut off immediately below the stitching 16, as seen in Fig. 9, the lip 30 can spring back into place over the groove, to close the same and provide a neat finish, thus concealing the seam and covering the groove.

In Fig. 10 of the drawings, parts hereinbefore described have been designated by numerals previously used, with the suffix "a." In this form of the invention, the welt 5 seam 24^a is used to hold the lip 30^a and the lining 13^a to the sole 1^a. This construction produces a stronger shoe than that delineated in Fig. 9, but its use is optional.

Having thus described the invention, what is claimed as new is:

1. In a shoe, a one part sole having an upper channel at its margin and a downwardly opening channel spaced inwardly from the first mentioned channel, an upper having its 15 lower edge fitting in the first mentioned channel, a welt, securing means extending through the welt, upper and sole between said channels, the welt extending upwardly over the securing means and resting on the 20 sole, and securing means fastening the welt on the sole.
2. In a shoe, a sole having its margin cut to provide a wing of reduced thickness and an upturned lip, said sole having a channel 25 between said wing and lip and a second channel spaced inwardly from the aforesaid channel and opening downwardly, an upper resting against said lip, a welt, securing means extending through the welt, upper 30 and sole between said channels, the welt being turned outwardly over said wing, and securing means fastening the welt on said wing.
3. In a shoe, the combination of elements 35 specified in claim 2 and further including securing means extending through the upper and lip to fasten them together.
4. In a shoe, a sole having its margin cut to provide an upper channel and having a 40 channel spaced inwardly from the aforesaid channel and opening downwardly, an upper fitting in the first mentioned channel, securing means fastening the upper to the sole and extending between said channels, a 45 shank on the sole, and securing means fastening the shank on the sole and extending downwardly into the second mentioned channel.
5. In a shoe, a sole having a heel seat, an upper having its counter portion turned 50 under the heel seat, a welt secured to the upper and fitting on the sole in front of the heel seat, a lift secured to the heel seat underneath the turned under portion of the upper, and securing means fastening the welt 55 on the sole and also fastening the shank portion of the lift to the sole.
6. In a shoe, a sole having a heel seat of reduced width providing shoulders, an upper having its counter portion turned under 60 the heel seat, a welt secured to the upper and turned outwardly over the marginal portion of the sole in front of said shoulders, said sole being channeled to accommodate the upper and welt, a lift secured to the 65 heel seat underneath the turned under portion of the upper, the shank edge of the lift and said shoulders of the sole having a lap joint, and securing means fastening the welt on the sole and extending rearwardly to also 70 engage the lift at said joint.
7. In a shoe, a sole having a heel seat of reduced width providing shoulders, and having a marginal channel extending forwardly from said shoulders, an upper having 75 portions fitting in said channel and a portion turned under the heel seat in rear of said shoulders, a welt secured to the upper within said channel and turned outwardly over the sole, a heel lift secured to the heel 80 seat underneath the turned under portion of the upper, the shank edge of the lift having an upper beveled surface, the sole and welt being beveled at said shoulders to overlap said beveled surface of the lift, and securing 85 means fastening the welt to the sole and extending rearwardly to engage through the beveled portion of the lift.

In testimony that I claim the foregoing as my own, I have hereto affixed my signature 90 in the presence of two witnesses.

AMOS MADSON.
